DESIGN FOR AN AXLE STAND

Alvin L. Johnson, Ottawa Hills, Ohio, assignor
to The Logan Gear Company, Toledo, Ohio, a
corporation of Ohio

Application May 6, 1937, Serial No. 69,206

Term of patent 7 years

To all whom it may concern:

Be it known that I, Alvin L. Johnson, a citizen
of the United States, residing at Ottawa Hills, in
the county of Lucas, State of Ohio, and United
States of America, have invented a new, origi-
nal, and ornamental Design for an Axle Stand,
of which the following is a specification, refer-
ence being had to the accompanying drawing,
forming part thereof.

Figure 1 is a side elevational view of an axle
stand illustrating my new design;

Figure 2 is a top plan view of the axle stand
shown in Figure 1.

I claim:

The ornamental design for an axle stand as
shown.

ALVIN L. JOHNSON.
